UNITED STATES PATENT OFFICE.

ALFRED WIEHL, OF BROOKLYN, NEW YORK.

ALBUM FOR PHONOGRAPH RECORDS.

Application filed January 12, 1924. Serial No. 685,745.

My invention relates to albums for the filing of phonograph records, and in some forms they may be racks, but in any case convenient durable units, which involve 5 many advantages. In particular, the invention is intended to provide for a maximum of convenience in access to remove, as well as to file records, to preserve them against injury, to provide such albums in form which may 10 be made at low cost and are durable.

Among the objects are to produce such albums or files in a compact form for a given number of records, to produce a file which will stand upright with the filing spaces for 15 each record maintained in an upright position, and still be most readily accessible while supporting the records in a manner permitting the quick inspection of the record name, and to accommodate a maximum number 20 of records in a given space.

In general the objects are compactness, convenience, durability, flexibility, safety, and to provide albums or files with these characteristics, or any of them, with great 25 economy. Improved files in accordance with these inventions, it may be noted, involve a further development of my inventions shown in Patents Nos. 1,402,332 and 1,424,054, the improvements providing for much cheaper 30 forms of albums or files suitable for particular purposes and more general use.

Particular embodiments of my invention are shown in the accompanying drawings, in which:

Fig. 1 is a perspective view of a triangular rack.

Fig. 2 is a fragmentary front view of lower spacers in such rack.

Fig. 3 is a vertical section of such rack 40 showing phonograph records in position.

Fig. 3^a is a perspective view of a rack with covering on smaller scale.

Fig. 4 is a perspective view of a triangular album, empty.

Fig. 5 is a side elevation in vertical section 45 with a record in position.

Fig. 6 is a top view of a modified album closed.

Fig. 7 is a top view of the album of Fig. 6, 50 shown extended.

Fig. 8 is a side elevation of the album shown in Fig. 6.

Fig. 9 is a perspective showing a slightly 55 modified album closed, and on smaller scale.

It will be noted that the album or rack as

illustrated in perspective Figs. 1 and 4, gives the general features of the triangular arrangement, which may be strictly triangular or may be slightly modified in some forms by the cutting of corners or the rounding of 60 some corners, without departing from the essentials of the structures. Likewise, in Figs. 3 and 5, it will be clearly seen how the records are positioned so that substantially half of the record is outside of the container or support, and in Fig. 5, in the album form, the centre portion containing the identifying name of the record, is clearly visible for inspection from the side by spreading the album leaves or series of containers. Figs. 70 65 4 and 7 likewise prominently feature the spreading of the album so that it stands upright and becomes a self-supporting unit; while the self-supporting upright nature of the rack appears clearly from the perspective view of Fig. 1. Thus the drawings 75 emphasize the convenience for insertion and the accessibility of the records, as well as the self-supporting of the same.

In Figs. 1 to 3^a, the box A has the substantially triangular sides a—a, at the bottom of which and disposed therebetween is a spacing rack B having a series of evenly spaced tooth members d, with slots therebetween of which slots D are shallow and slots C relatively deeper, and alternating at top and bottom adapted to receive records in staggered relation and to firmly hold the same when positioned. At the top of the box another spacing rack E is oppositely positioned, with slots C, D complementary to those in the bottom spacer B. The plane of the outer face of these slotted racks B and E substantially bisects a record inserted in supported position,—so that the half of the record projects and is accessible, while the triangular configuration of the rack, and its position with the rack face inclined, as shown, permits each record to be inserted with convenience and to roll into its position and to stay in position by its own weight.

Such racks or files may, without any cover, be slid onto a shelf or into a cabinet, and are amply protected, or they may be 105 arranged to pull out with a stop or a suitable hinge, of any well known type, permitting them to be turned ninety degrees, because the diametrically opposite spacing supports will equally support the records through- 110

out a ninety degree displacement of the rack or file about the apex of the triangle. They may be made without the cover in cases such as when the files are stacked on a shelf which protects them from dust, or put into a cabinet, because they admirably serve for temporary use of a table and during such use have all the advantages for accessibility and support, being prevented from rolling out. When desired such files may be made with covers such as of approximately triangular shape and hinged to the diagonal edge of the box sides α , having edge strip portions which when the covers are open provide additional breadth of base to make the upright position of the file more stable. The dotted position F' shows how the cover closes to protect the portion of the records projecting from the triangular file, and on the inside of the file cover a suitable index G may be printed or pasted where most convenient for reference to the contents of the file, while a clip f of any suitable kind, will provide for secure holding of the cover halves in closed position,—and when closed the entire box will appear as shown, in dotted lines partially in Fig. 1 and in full lines in Fig. 3^a, a symmetrical package suitable for shipping or carrying. It will be noted that the cover F' , as illustrated in Fig. 3^a, may be a one-piece triangular cover adapted to fit over file box proper so that the empty files, before use, with cover will be complete in triangular form and therefore two complete files may be shipped or stored in the space of what otherwise would be a completely closed file box. This feature would involve great economy in space in shipping and storing before use.

The album form of this invention while subject to various modifications comprises the substantially right triangular envelopes H , having at their lower triangular apex a spacer h slightly greater than the thickness of a record. On the hypotenuse of the right-angle triangular conformation of these envelopes their edge may be preferably cut away as indicated at J , so that the entire name marking of the record when filed may be read without taking the record out of the envelope. This is made possible by the spreading of the album leaves which are bound at hinge K along one side of the right-angle triangular conformation of the album permitting the other side of the triangular envelope to swing freely between the covers L , L , or with the slight drag of the envelopes when weighted down by a record and the slight yield at the hinge, the lower side of the envelope will rest on the table in contact with the edge of the covers L , L , and strengthening may be provided by reinforcements h' .

As shown in dotted lines, Fig. 5, the covers may be triangular, but hinged on their diag-

onal corresponding to the face of the enclosed pockets or envelopes H , H , so that the portion L' of each cover may be closed up to protect the sides of the records and thereby form a completely square closed album, and when in use the side L' will be turned down respectively on each side, as shown in Fig. 4, with one edge in contact with the table or support, thereby giving an added base support to maintain the album upright, and when so hinged the contained records will be visible from either side due to the spreading of the hinged envelopes so as to make all intermediate records in the file accessible and their names readily readable without removal. In all the forms of the invention, the triangular form, with a right-angle triangle when the hypotenuse is inclined, provides for one side forming the base, and form-receiving pockets so positioned that records will roll easily into the pockets over the bottom spacer h and will be retained securely in the pocket while the album is in upright position, by the stop or spacer h .

In the modified form of album shown in Figs. 6 to 9, to prevent the album leaves from being spread too far apart, a clip comprising a pair of hinged links M , such as illustrated in Figs. 6 and 7, suitably limits the movement, and when in open position such connection is out of the way of the records,—but when closed, as shown in Fig. 6, the so-formed spacer M turns to a position whereby the ends of the two links form a projection M' directly over the top of the records in a manner that holds the records in their pockets although the closed album may be turned up side down. The detailed formation of such spacer hinge serving alternately as spacer and record-holding clip may be modified in many ways, but its general purpose is served by the form shown, which may also have a snap catch N which holds the clip in closed position, thereby holding the covers L , L together during any incidental handling. In such forms the covers or sides L'' , are stiff, and preferably one corner l is curved to approximate the curvature of inserted records, so that one curved corner of the album becomes a distinctive feature showing that the album is to stand upon one of the straight sides. As shown in Fig. 9, such album covers may also have box edges O which completely enclose the leaves of the album, and, furthermore, the straight ones, but not O , serve as an additional base for sustaining the album in an upright position when open.

It will thus be seen that the general configuration of album or file with pockets or racks with inclined edges, is provided, in the forms shown, as a box or album adapted to stand on edge, and to be securely maintained for all practical purposes of inspection and use upon a flat base, so that the

insertion of records and the removal of records is made from the side and top, thereby providing convenience and a secure upright holding of the records admirably 5 adapted for compact and convenient filing, and of great convenience for inspection particularly in the case of the album where the entire legend or name label of the record can be readily viewed without removal of 10 the record. In the various forms they also provide for convenient carrying or transportation in file, and in the case of the rack boxes, such are peculiarly well adapted to be inserted on edge on shelves or in cabinets 15 in ways that make them readily accessible, though fully protected by the cabinet without any special cover on the file cases. When in use these files provide alignment of support on the sides of the records in the oblique 20 position which, as a rule, will constitute substantially the hypotenuse of a right-angle triangle form of pocket or envelope, but modifications may involve the same oblique supporting line with changes in configuration 25 of the remainder of the file case or album, and this may be done in some cases without loss of attendant advantages.

While many modifications may be made 30 in detail without departing from the spirit of my invention from what is herein specifically shown and described, what I claim and desire to secure by Letters Patent is:

1. A phonograph record file comprising right-angle triangular record-holding means 35 open to receive records on the side of the hypotenuse and hold a plurality of records, means forming a permanent part of the file to support said container upright on one of the short sides of the triangle, and 40 means adjacent the acute angle near the base to hold each record substantially half enclosed in said file.

2. A portable phonograph record album comprising a plurality of pockets each of a 45 right-angle triangular form and having a receiving opening at the long side of the triangle, means to support said pockets in an upright position and to hold them together along one of the short sides, with the other

short side cooperating with said pockets to 50 form a supporting base.

3. A portable phonograph record album comprising right angle triangular pockets open on the hypotenuse, means to bind said pockets together along the normally upright 55 short side of the triangle, a stop in each pocket at the acute angle away from the bound edge to prevent the record from rolling out, and outside covers supported from the bound edge adapted to spread and provide a horizontal base support.

4. A phonograph record file comprising a plurality of right-angle triangular pockets, means to support the pockets in vertical planes with the hypotenuse forty-five degrees 60 from the base and with an opening for filing the records in each pocket on the hypotenuse.

5. A portable right angle triangular phonograph record file having one short side of the triangle forming a horizontal base 70 with associated means for normally maintaining the file with said short side base in its horizontal position when set up for use, and a cover secured to the triangular file.

6. A record album comprising a plurality 75 of triangular pockets each having its receiving opening on the longest side of the triangle and means at the lower forward corner of each triangular pocket to guide the respective record into secure position and 80 prevent it from rolling out.

7. A phonograph record file having a portable plurality of pockets in effect of triangular shape with a short side positioned horizontally to form the base, main supporting guides each formed by the sides of each pocket at its open edge for engagement of a record at substantially diametrically opposite points of each record, whereby substantially half of the record is enclosed with the bottom forward support for 90 each record in position to prevent it from rolling out.

In testimony whereof, I have signed my name to this application, this 5th day of 95 January, 1924.

ALFRED WIEHL.
